(57) **CLAIM**

The ornamental design for a sport shoe as shown and described.

DESCRIPTION

FIG. 1 is a perspective view of a sport shoe showing my new design;

FIG. 2 is another perspective view thereof;

FIG. 3 is a top plan view thereof;

FIG. 4 is a bottom plan view thereof;

FIG. 5 is a left side elevational view thereof;

FIG. 6 is a right side elevational view thereof;

FIG. 7 is a rear elevational view thereof;

FIG. 8 is a front elevational view thereof;

FIG. 9 is an enlarged view of portion "9" in FIG. 1; and,

FIG. 10 is an enlarged view of portion "10" in FIG. 2.

The dot-dash-dot broken lines shown in FIGS. 1, 2, 9, and 10 define the boundaries of the enlargements and form no part of the claimed design.

1 Claim, 10 Drawing Sheets
